UNITED STATES PATENT OFFICE.

ROY DRUMMOND, OF SEATTLE, WASHINGTON.

WRENCH.

1,106,932.

Specification of Letters Patent. Patented Aug. 11, 1914.

Application filed March 9, 1914. Serial No. 823,546.

To all whom it may concern:

Be it known that I, ROY DRUMMOND, a citizen of the United States of America, and a resident of the city of Seattle, in the county of King and State of Washington, have invented certain new and useful Improvements in Wrenches, of which the following is a specification.

My invention has for its aim to provide a tool of the above character consisting of two elements whereby a wrench of simple and durable construction is obtained to operate in an efficient manner.

Those features of construction, arrangement and combination of parts on which I desire protection are succinctly defined in the appended claims, and for a full understanding of the same reference is to be had to the following specification and the accompanying drawing wherein:

Figure 1 is an elevation of my wrench. Fig. 2 is an edge elevation, a portion of the pivoted jaw being in section, and Fig. 3 is a view similar to Fig. 1, the pivoted jaw being employed in a different position.

It may be preliminarily stated that in the preferred embodiment, illustrated in the attached drawings, there are employed a shank, provided with a curved jaw face and a serrated jaw face, and a jaw pivoted to the shank for movement to a position to cooperate with either of the shank jaw faces.

Referring by like characters of reference to like parts throughout the several views of the drawings and the specification, 1 designates a shank conveniently formed on one end portion to provide a handle and having its opposite end portion fabricated in the form of a fixed jaw 1' with a curved 20 jaw face 2 on one side and on the opposite side a series of serrations 3 constituting another jaw face. The jaw 4 is pivoted, as by pin 5, to the fixed jaw 1' and comprises a pair of plates providing spaced arms or 30 extensions 6 to receive the aforesaid fixed jaw, the outer end portions of the plates being pressed together to form the reduced solid jaw body 7. The jaw is reduced, as shown, to directly oppose or lie entirely 40 within the plane of the fixed jaw 1', this construction being especially advantageous when operating on small or thin nuts as the outer jaw portions may lie flat or flush on a surface. The free end of the movable jaw 50 is turned to provide a lip or hook 8 to more effectively grip the article. Arms 6 have

their inner edges curved or of arcuate formation and provided with teeth to produce jaw faces 6' adapted for coöperation with either face 3 or jaw face 9, the latter being 60 formed in a plane, on fixed jaw 1', within the curvature of smooth face 2 whereby a shoulder 2' is formed to afford a more secure grip on a pipe. A shoulder 7', disposed between jaw body 7 and faces 6', opposes lip 65 8 and defines therewith a pocket or seat for a nut. The jaw face of body 7 and faces 6' are each adapted for coöperation with face 3. Swinging the jaw 4 over the end of jaw 1' from the face 2, which is especially 70 adapted for nuts and the like having straight edge portions, the jaw 4 may be used in coöperation with the serrated face 3 for operating on pipes or the like. This latter arrangement may also be employed for 75 nuts when a shorter leverage is required.

The foregoing detailed description has been given for clearness of understanding only, and no undue limitation is to be understood therefrom, but the appended claims 80 are to be construed as broadly as is permissible in view of the prior art.

Having thus described my invention, what I claim as new, and desire to secure by Letters Patent, of the United States of America, is:—

1. A wrench comprising a shank element formed with a fixed jaw having a curved smooth jaw face and a serrated jaw face leading from the smooth jaw face, and a 90 movable jaw adapted for coöperation with the faces of the fixed jaw and having a smooth flat jaw face formed with opposing shoulders to receive a flat surface and a curved serrated jaw face.

2. A wrench comprising a shank element formed with a fixed jaw having a curved smooth jaw face and a serrated jaw face leading from the smooth jaw face and lying within the plane of curvature of the latter 100 face to provide a shoulder between the faces, and a movable jaw adapted for coöperation with the faces of the fixed jaw and having a flat jaw face formed with opposing shoulders to receive a flat surface and a curved 105 jaw face to oppose the serrated face of the fixed jaw.

3. A wrench comprising a shank element formed with a fixed jaw having a smooth face and a serrated face on one side and a 110 curved serrated face on the other side of the fixed jaw, and a jaw pivoted to the fixed

jaw and formed with a flat face to coöperate with the smooth face of the fixed jaw and a curved face to coöperate with the adjacent serrated face of said fixed jaw, said pivoted 5 jaw being adapted to swing to oppose the curved serrated face of the fixed jaw whereby either jaw face of the pivoted jaw is adapted for coöperation with the last named face of the fixed jaw.

10 4. A wrench comprising a shank element formed with a fixed jaw having a curved jaw face, and a movable jaw pivoted to the

shank element and provided with a curved jaw face and a flat jaw face leading from the latter, said pivoted jaw also being formed 15 with a shoulder extending outwardly from the flat jaw face at the inner end thereof to be intermediate the jaw faces.

Signed at Seattle, Washington, this 10th day of February, 1914.

ROY DRUMMOND.
